G. S. VIVIAN
DEVICE FOR SECURING FOUNTAIN PENS AND THE LIKE
IN POCKETS OF CLOTHING AND THE LIKE
Filed May 3, 1930

UNITED STATES PATENT OFFICE

GEORGE STEWART VIVIAN, OF LONDON, ENGLAND, ASSIGNOR OF ONE-HALF TO T. E. FORD LIMITED, OF HIGH WYCOMBE, BUCKINGHAMSHIRE, ENGLAND

DEVICE FOR SECURING FOUNTAIN PENS AND THE LIKE IN POCKETS OF CLOTHING
AND THE LIKE

Application filed May 3, 1930, Serial No. 449,603, and in Great Britain May 7, 1929.

This invention relates to clips and other like devices adapted to be attached to fountain pens, refil pencils and the like for the purpose of securely holding the pen or the like in a pocket of clothing. The usual practice is to provide a split spring band effect from and integral with a finger the free end of which is resiliently pressed towards the side of the pen, the band embracing the pen and being slid along the pen to adjust the position of the clip in accordance to the depth of the pocket or the like into which the pen is to be inserted. With most of such clips the spring band loses its resiliency or does not properly fit the pen with the result that it slips along the pen and cannot be relied upon to remain in the predetermined position on the pen. To overcome this defect some fountain pens and the like have clips permanently attached to them but these are not adjustable along the pen and consequently if the pocket adapted to receive the pen is not of a certain depth the clip will not properly engage the edge of the pocket.

The object of the present invention is to provide a securing device for fountain pens and the like which will have the advantage of being adjustable on the pen or the like but will not slip along the pen.

According to my present invention the usual cover cap or other appropriate part of a pen or the like and the clip or equivalent member are provided with co-operating parts adapted to fit one into the other so as to prevent relative endwise movement of the clip and pen but permitting removal of the clip, means being provided to enable the point of engagement of the clip with the pen to be varied.

By the expression "clip" it is understood that any securing member for attachment to a fountain pen or the like is contemplated, in which the securing member is adapted to be engaged with a pocket of a coat or the like.

For instance instead of the usual depending finger a depending pin may be employed, the invention more particularly being concerned with the part of the securing device which takes the place of or corresponds to the usual spring band.

In one form of the present invention the cap of a fountain pen or the like carries around a reduced diameter part of its circumference a number of collars between a selected pair of which a substantially annular lateral extension of the clip is engaged, the collars being held in position by an end member threaded on to the upper end of the cap.

In another form of my invention the cap of the pen or the like is of the known type containing a concentric sleeve portion the inner end of which is preferably adapted to abut against the nib end of the fountain pen body, and this inner concentric portion is formed with a number of spaced circumferential grooves or channels in which is selectively engaged a substantially half annular or fork like lateral extension of the clip.

In order that my invention may be clearly understood and readily carried into effect I have appended hereto a sheet of drawings illustrating examples of the two foregoing forms of my invention, and wherein:

Fig. 1 is a sectional side elevation of the pen cap and clip showing the second of the two forms of my invention above referred to.

Fig. 2 is a half sectional front elevation of Fig. 1.

Fig. 3 is a sectional plan view on the line 3—3 of Fig. 1.

Fig. 4 is a sectional side elevation showing the other form of my invention referred to.

Fig. 5 is a rear elevation view of Fig. 4, and

Fig. 6 is a sectional plan view on the line 6—6 of Fig. 4.

Referring to Figs. 1, 2 and 3 of the drawings the fountain pen 1 is shown with a screw-on cap 2 in which a concentric sleeve-like part 3 is adapted to be pressed against the annular end 4 of the pen from which the nib 5 extends so as to form an effective seal against the leakage of ink. The inner part 3 is formed with a number of spaced circumferential grooves or channels 6 and is formed with a threaded part 7 screwed into an internal thread 8 on the cap 2 whereby the inner sleeve-like part 3 is removable.

from the remainder of the cap which is normally closed at its upper end by a flange-like head 9 integral with the sleeve 3, the upper end of the cap 2 preferably being inclined or tapered as indicated at 2a, the inner face of the head 9 being correspondingly inclined to provide a good seating of these two parts. The periphery of the head 9 is preferably milled or serrated to facilitate 10 turning.

The cap 2 is slotted vertically at one point for a portion of its length as indicated at 10, this slot 10 extending through the upper end of the cap 2 and providing a guide for the 15 neck 11 of the clip 12, the clip 12 being specially shaped for this purpose. The neck 11 of the clip carried the part of the clip adapted to secure the clip to the cap 2, and such part is selectively engaged with the circumferential grooves 6. For this purpose the clip 12 has a substantially semi-circular or half annular extension 13 from the neck 11 and this extension has an inner edge 20 mentioned to engage in a groove 6, its outer edge being close to or engaging the inner surface of the cap 2 as shown in Fig. 3.

Should the depth of the pocket into which the pin is to be inserted necessitate a change of position of the clip along the cap 2, the 30 head 9 of the sleeve 3 would be rotated to withdraw the sleeve 3, the clip 12 sliding along the slot 10 until it is free of the cap 2 and can be withdrawn from one circumferential channel 6 and introduced in another, 35 when the sleeve 3 can be threaded into the cap again with the neck 11 of the clip engaged in the slot 10.

If desired, instead of a number of circumferential channels 6, the cap 2 (or the sleeve 40 3) can be formed with a reduced diameter upper part 14 as shown in Figs. 4, 5 and 6, such reduced diameter part 14 having a number of collars 15 fitted over it and retained in position by a nut or the like threaded on to 45 the upper end of the reduced diameter part 14. For instance if the pen is of the type employing an inner sleeve 3, the upper end 9a of this sleeve can be a flange as shown formed with an internal thread 9b, threaded 50 over the upper end of the cap 2. Instead of employing a substantially semi-circular part 13 with the clip 12 as shown in Fig. 3, it is preferred in the present instance to make such part completely annular or circular as shown 55 at 16, the diameter of this ring corresponding to that of the collars 15.

It will be appreciated that when it is desired to change the position of the clip 12 relative to the cap 2 this can be effected by 60 screwing the head 9a to release the collars 15 and ring 16, and to replace the collars with the ring 16 between a different pair.

To improve the appearance of the cap 2, the collars 15 may be of the same material as the 65 clip or if desired washers or rings can be fitted

between the collars 15 not having the ring 16 between them, these washers or rings being similar to the ring 16.

By means of my invention a neat and desirable method of securing fountain pen clips 70 and the like is provided which obviates the present disadvantages.

I claim:

1. In a fountain pen, a nib cover cap, a pocket clip and means in said cover cap for 75 selectively securing the clip immovable axially relative to the cover cap at a number of points between the ends of the cover cap.

2. A fountain pen nib cover cap comprising a tubular member, a number of collars disposed about it, and a pocket clip adapted to be gripped between a pair of said collars. 80

3. A fountain pen nib cover cap, comprising a tubular member, a pocket clip, an inner concentric tubular member adapted to receive the 85 nib, and a number of channels around said inner tubular member with which is selectively engaged one end of the pocket clip.

4. A fountain pen nib cover cap comprising a tubular member adapted to be engaged 90 over the pen body, a pocket clip, an inner concentric tubular member adapted to be engaged over the nib, a flanged head on the outer end of said inner tubular member closing the outer end of the other tubular member, a slot 95 in the outer tubular member exposing the inner tubular member, a number of circumferential channels around said inner member and a substantially semi-annular extension of the pocket clip engaged with one of said channels. 100

5. A fountain pen nib cover cap comprising a tubular member adapted to be engaged over the pen body, a pocket clip, an inner concentric tubular member adapted to be engaged over the nib, a flanged head on the outer end of said inner tubular member closing the outer end of the other tubular member, a slot in the outer tubular member exposing the inner tubular member, a number of circumferential channels around said inner member, a circumferentially threaded enlargement on said inner tubular member, a threaded portion in said outer tubular member threaded over said enlargement, and a 110 substantially semi-annular extension of the pocket clip engaged with one of said channels. 115

6. A fountain pen nib cover cap comprising an outer tubular member adapted to be engaged over the pen body, an inner concentric tubular member threaded to said outer tubular member, an annular abutment on said outer member and a flanged head on the outer end of said inner member constituting 120 a second abutment, a number of collars disposed around the outer tubular member between said abutments, and a pocket clip 125 formed with a part adapted to be engaged between a pair of said collars. 130

7. A fountain pen nib cover cap comprising an outer tubular member adapted to be engaged over the pen body, an inner concentric tubular member threaded to said outer tubular member, an annular abutment on said outer member and a flanged head on the outer end of said inner member constituting a second abutment, a number of collars disposed around the outer tubular member between said abutments, a pocket clip formed with a part adapted to be engaged between a pair of said collars, said part comprising an annular ring adapted to be slipped over the said outer tubular member.
